UNITED STATES PATENT OFFICE.

ERNST OLDENBUSCH, OF JERSEY CITY, ASSIGNOR TO WILLIAM SCHIMFER
& CO., OF HOBOKEN, NEW JERSEY.

BAG-FASTENING.

SPECIFICATION forming part of Letters Patent No. 449,912, dated April 7, 1891.

Application filed January 9, 1891. Serial No. 377,220. (No model.)

To all whom it may concern:

Be it known that I, ERNST OLDENBUSCH, of Jersey City, in the county of Hudson and State of New Jersey, have invented a new 5 and useful Improvement in Fastenings for Bags, of which the following is a specification.

My invention relates to an improvement in fastenings for bags, and more particularly to fastenings for securing the ends of the flaps 10 to the ends of the body portion.

The fastening is particularly well adapted to be applied to a bag in which one of the flaps is provided at its free edge with an overlapping frame-piece—such, for example, as 15 that shown and described in Letters Patent No. 437,366, granted to Albert H. Peterson on September 30, 1890—the ends of the overlapping frame-piece being turned downwardly in position to engage the opposite ends of the 20 satchel.

A practical embodiment of my invention is represented in the accompanying drawings, in which—

Figure 1 represents a top view of the satchel-frame, showing the fastenings in position as 25 in use. Fig. 2 is a longitudinal vertical section taken through one of the fastenings and the portions of the frame adjacent thereto. Fig. 3 is a top view in detail of the fastening, 30 the top of the cap being removed to show the latch and hook or catch more clearly. Fig. 4 is an end view of the fastening and parts of the frame adjacent thereto; and Fig. 5 is a transverse section through the fastening, 35 showing the catch and portions of the frame adjacent thereto in elevation.

A represents the overlapping frame-piece or guard, secured to the free edge of one of the flaps and provided at its ends with turned-down portions *a*, which are intended to rest 40 in proximity to the ends of the body of the satchel. The end cross-pieces, which form the outer edges of the ends of the body portion of the satchel, are represented by *B*, and to their 45 outer faces the body portion *C* of the catch or hook is secured. In the present instance I have shown it secured to the frame-piece by means of rivets *c'*. From the body portion *C* a neck portion *c* extends upwardly and 50 terminates at its upper end in a hook *c*², leav-

ing a space *c*³ between it and the neck *c* for the reception of the swinging latch *D*.

The latch *D* is pivotally secured at one end to the top *e* of a cap or housing *E*, and its free end projects through an elongated slot *e'* in 55 a downwardly-turned end *e*² of the said housing. The housing *E* gradually widens as it extends toward the free end of the latch *D*, and its downwardly-turned end *e*² is intended to rest snugly against the outer face of the 60 downwardly-turned end *a* of the overlapping frame-piece *A*. The housing *E* is fixed firmly to the piece *A* in the present instance by means of a lug *e*³ at its inner end, which is adapted to extend downwardly through a suitable 65 opening in the piece *A* and clinch upon the under side of said plate, and by means of a rivet *e*⁴, extending through the downwardly-turned end *e*² of the housing *E* and through the downwardly-turned end *a* of the piece *A*. 70 I have represented the latch *D* as provided with a notch *d*, the bottom of which is intended to engage the lower face of the hook *c*² within the notch *c*³, and the outer end of the said latch outside of the housing I have provided 75 with a ball or knob *d'* for convenience in swinging the latch.

The hook portion of the catch extends in a plane substantially parallel with the end of the bag, and the latch *D* is pivoted to the 80 housing, so as to swing in a horizontal plane substantially at right angles to the plane of the catch. The hook portion of the catch projects upwardly through an opening *a'* in the frame-piece *A* between the downwardly-turned end *a* and the cross-piece *B*, and its hook portion is so located that the latch can 85 be swung into engagement therewith only when the flaps are tightly closed.

To prevent the latch *D* from unintentional 90 displacement, I locate a flat spring-plate *F* between the latch *D* and the top of the housing and secure it in position by the pivotal rivet *f*, which secures the latch to the housing. The free end of the spring-plate *F* is turned 95 downwardly, as shown at *f'*, and exerts a constant tension upon the latch, thereby making the friction so great as to require a positive push upon the free end of the latch to operate it.

What I claim as my invention, and desire to secure by Letters Patent, is—

1. The combination, with the overlapping frame-piece having its end turned downwardly to project over the end of the bag, of a catch fixed to the end of the bag between it and the downwardly-turned end of the frame-piece and projecting upwardly through the frame-piece, a latch-housing, and a latch having a swinging movement in proximity to the face of the frame-piece to engage the catch and projecting through the downwardly-turned end of the housing, substantially as herein described.

2. The combination, with the overlapping frame-piece and a housing fixed to its face, of a swing-latch pivotally secured to the housing and having a swinging movement along the face of the overlapping frame-piece, a friction-spring within the housing, having a bearing upon the latch to prevent its unintentional displacement, and a catch fixed in position to engage the swinging latch, substantially as herein described.

ERNST OLDENBUSCH.
